(57) **CLAIM**

The ornamental design for an axe for splitting wood into kindling and the like, as shown and described.

DESCRIPTION

FIG. 1 is an isometric view of the front, bottom, and left side of my new design;

FIG. 2 is a left side elevation view thereof, the right side being a mirror image;

FIG. 3 is a bottom view thereof;

FIG. 4 is a top view thereof;

FIG. 5 is a front elevation view thereof; and,

FIG. 6 is a rear elevation view thereof.

The broken lines in the drawings are directed to features of the axe that form no part of the claim.
